UNITED STATES PATENT OFFICE.

PATRICK FORSYTH, OF CINCINNATI, OHIO.

IMPROVEMENT IN DEVICES FOR CHANGING HEADS IN NEWSPAPERS.

Specification forming part of Letters Patent No. 159,172, dated January 26, 1875; application filed October 22, 1874.

To all whom it may concern:

Be it known that I, PATRICK FORSYTH, of Cincinnati, Hamilton county, Ohio, have invented a new and useful Device for Changing Heads in Newspapers, of which the following is a specification:

The invention relates to a device to facilitate the removal, replacement, or substitution of any desired portion of a column in the form from which a newspaper is printed—such, for example, as heads and sub-heads of advertisements.

My contrivance consists, essentially, of a bed, block, or body, having on its working face an interrupted dovetail groove or channel, into which a correspondingly-dovetailed shallow electrotype may be inserted, or from which it may be withdrawn without interference with the column of type on the other side of the margin. My contrivance further comprises a self-closing catch, whereby the said separable type is firmly locked in position for printing, said catch being readily released for withdrawal of the type, as above, by means of a point or stylus in the hands of the printer.

In the accompanying drawing, Figure 1 is a perspective view, representing one of my bed-blocks in position, and ready for the reception of the electrotype-plate, which is shown detached. Fig. 2 is a plan representing the same parts, with the plate partially inserted, a portion of the neighboring column of the adjacent page being represented. Fig. 3 shows the plate locked in position on the bed. Fig. 4 is a longitudinal section through the plate and bed. Fig. 5 is an under-side perspective view of my bed. Fig. 6 shows a bed and corresponding plate with four interruptions in place of one, as in the preceding figures.

The outer surface *a* of my bed *A* is depressed as much below the general face of the matter as the depth of the electrotype *B*. Rising from said surface *a*, parallel with the lines of matter, are two series of interrupted curbs or flanges, *C c C' c'*, which fit and embrace corresponding dovetail projections *D d D' d'* from the upper and lower edges of the type.

One interruption is here shown for each

flange; but, for a narrow margin, withdrawal of the plate, without interference with the neighboring column, may be secured by a greater number of interruptions with correspondingly-shorter flanges, as in Fig. 4.

The end of the plate *B* last inserted has a recess, *b*, for the projecting portion *e* of catch *E*, which occupies dovetailed slot *a'* in the corresponding end of the bed. A screw-threaded pin, *F*, which occupies a slot, *c'*, of said catch, limits the upward movement of the same. A spring, *G*, causes the automatic closure of the catch *E* the instant that the latter is left at liberty. An upward projection, *H*, from the catch affords a convenient surface for the impact of a point or stylus, whereby the catch may be depressed so as to enable the withdrawal or insertion of the plate by the compositor.

I represents the separating-rule of the contiguous column of type, and *J* a portion of the "chase."

My device may be formed to withdraw either to right, as shown, or, by reversing the parts, to the left, for use in the opposing page; or the same block may be effective, in the respective positions, by simple reversion.

The common margin or interval between two adjacent pages of a newspaper is not commonly as great as the width of a column, and hence the necessity of a mode such as described of so fastening the plate as that it can be separated, by an endwise movement, considerably less than the width of a column.

I am aware that it has been proposed to secure separable electroplates by dovetail grooves in the face of the block, and I therefore make no claim to such, broadly considered; but

I claim herein as new and of my invention—

The bed *A*, having the interrupted flanges and spring-catch *E* to receive and hold the interrupted dovetailed projections of the type-plate *B*, substantially as and for the purpose designated.

In testimony of which invention I hereunto set my hand.

PATRICK FORSYTH.
